CLAIM

The ornamental design for a fishing line spooler as shown and described.

DESCRIPTION

FIG. 1 is a front perspective view of the fishing line spooler; FIG. 2 is a rear perspective view of the fishing line spooler of FIG. 1;

FIG. 3 is a left side profile view of the fishing line spooler of FIG. 1;

FIG. 4 is a right side profile view of the fishing line spooler of FIG. 1;

FIG. 5 is a right side and bottom perspective view of the fishing line spooler of FIG. 1;

FIG. 6 is a left side and bottom perspective view of the fishing line spooler of FIG. 1;

FIG. 7 is a right side and top perspective view of the fishing line spooler of FIG. 1;

FIG. 8 is a left side and top perspective view of the fishing line spooler of FIG. 1;

FIG. 9 is a top profile view of the fishing line spooler of FIG. 1; and,

FIG. 10 is a bottom profile view of the fishing line spooler of FIG. 1.

The broken lines shown in the Figures represent portions of the fishing line spooler that form no part of the claimed design.

1 Claim, 10 Drawing Sheets
